(57) **CLAIM**

The ornamental design for a steam iron, as shown and described.

DESCRIPTION

FIG. 1 is a front, left perspective view of a steam iron, showing my new design;

FIG. 2 is a rear, right perspective view thereof;

FIG. 3 is a rear, left perspective view thereof;

FIG. 4 is a front elevational view thereof;

FIG. 5 is a rear elevational view thereof;

FIG. 6 is a left side view thereof;

FIG. 7 is a right side view thereof;

FIG. 8 is an enlarged top plan view thereof;

FIG. 9 is an enlarged bottom plan view thereof;

FIG. 10 is an enlarged view of detail 10 in FIG. 2;

FIG. 11 is an enlarged view of detail 11 in FIG. 3;

FIG. 12 is an enlarged view of detail 12 in FIG. 5;

FIG. 13 is an enlarged view of detail 13 in FIG. 6; and,

FIG. 14 is a front, left perspective view of the steam iron in a detached state.

The dashed broken lines in the figures are for the purposes of illustrating portions of the steam iron that form no part of the claimed design.

The dash-dot-dash broken lines are for notating enlarged views and form no part of the claimed design.

1 Claim, 12 Drawing Sheets
